DOOR STOPPING AND HOLDING DEVICE

George G. Wyckoff, Chicago, Ill.

Application November 4, 1940, Serial No. 364,114

8 Claims. (Cl. 292—78)

This invention relates to a door stopping and holding device used in connection with a swinging door that is usually provided with a stop at the base-board or at its lower end to limit its opening movement.

An object of the invention is to provide a simple, sturdy and inexpensive device of this type which will serve as a stop to limit the opening movement of the door and will at the same time hold the door in open position. The device is small and compact, and projects a minimum distance from the door so as to eliminate any interference with the use of the space adjacent the door opening.

A further object of the invention is to provide an improved construction in which the opening movement of the door is checked before the door is brought to a stop and is held in its open position against drafts or slight impulses that often release a door and cause it to close.

More specifically the invention is directed to a construction employing a swinging member pivotally mounted preferably at the lower end of the door and is adapted to swing outwardly to align with and engage a projection or rise on the floor whereby to ride upon such projection and to be forced into a door holding position. In this position, the door will resist a draft or other jarring force that may come against it but will readily release the swinging member when the door is intentionally pulled closed. The structure comprises few rigidly constructed parts devoid of springs or other members that require attention and repair at intervals.

Other objects and advantages of the invention will be apparent in the following detail description taken in connection with the accompanying drawing which forms a part hereof.

In the drawing:

Figure 1 is a perspective view of a portion of a door employing a device embodying the present invention;

Fig. 2 is an end view of the door and device shown in Fig. 1, with a portion in section to illustrate the manner of stopping and holding the door in open position;

Fig. 3 is a vertical sectional view of this device illustrating the manner of attaching the same to the door and the position of a swinging member which holds the door in open position;

Fig. 4 is a top view of the device attached to the door but illustrating the cover in section;

Fig. 5 is a sectional view taken along line 5—5 of Fig. 3;

Fig. 6 illustrates a variant embodiment of the invention;

Fig. 7 is a detail sectional view of the lower end of the swinging member to illustrate another variant embodiment of the invention; and

Fig. 8 illustrates the manner of mounting the projection on the floor where a carpet covers the floor.

The device illustrated in the drawing as showing a preferred embodiment of the invention comprises a vertically swinging member 5 pivotally mounted adjacent the lower edge 6 of door 7 by any suitable attaching means which may be a U-shaped bracket 8 secured to a face of the door by screws 10. Bracket 8 preferably has its cross leg 11 positioned against the door and screws 10 enter openings in the same so that they may be forced into the door to hold this bracket securely thereagainst. Swinging member 5 is pivotally mounted to move between opposed legs 12 of this bracket 8. The pivotal mounting may consist of a pin 13 passing through the upper part of swinging member 5 as well as opposed legs 12, so that the ends may be headed, as illustrated 14, upon the outside face of legs 12.

Swinging member 5 may comprise a tube or like hollow member 15 that extends downwardly to the floor when suspended in a vertical position from pivot 13. The lower face 16 of tube 15 is adapted to clear the floor and be spaced thereabove a predetermined distance, preferably a distance permitting it to swing outwardly, as shown in Figs. 1 and 2, without touching the floor. Normally, swinging member 5 is held in this position by resting against a pair of detents 17 formed in side walls 12. When door 7 is moved to open position, lower end 16 of swinging member 5 is adapted to engage and ride upon a projection or rise on the floor, such as the head 19 of a screw 20. The manner in which lower end 16 will engage screw head 19 is illustrated in Fig. 2. The force of the opening movement will cause swinging member 5 forcibly to bear against detents 17. The pressure will result in a spreading of these detents to permit member 5 to snap therebeyond in the position shown in Figs. 4 and 5. Hence, these detents 17 initially act as a check to restrain the force of the opening movement of door 7 and aid to arrest the door in its open position. Detents 17 are spaced, with respect to cross leg 11 of bracket 8, to provide a snug fit for member 5 between the same and this cross leg 11 when latched in its vertical door holding position. The door will be held

40

tightly in this position and rattling of the door by drafts will be prevented.

The lower end 16 of swinging member 5 is preferably adjustably mounted so as to permit a predetermined spacing thereof above the floor. This adjustment is desirable because it eliminates making the mounting of the device upon the door critical with respect to its height above the floor and further eliminates difficulties in its operation as the result of variations in the level of the floor. To this end, tube 15 of member 5 is adjustably carried with respect to an upper part 21, which receives pivot 13. As illustrated in the drawing, tube 15 is internally threaded at its upper end to receive this upper part 21, the latter being in the instant disclosure in the form of a threaded bolt and a lock washer 22. In the event the lower end 16 extends too far from the floor, member 5 might be pulled free of screw head 19 without kicking past detents 17 to its inclined position shown in Figs. 1 and 2. Upon a subsequent opening movement of the door, the forward edge of lower end 16 will strike against the bolt head 19 instead of clearing the same, as illustrated in Fig. 2. Member 5 will then be unable to engage over head 19 to act as a stop and hold the door in open position. It is, therefore, desirable to have an adjustment that can be conveniently made by anyone after the device is mounted upon the door. Any form of adjustment may be provided, and consequently, I do not wish to be limited to the exact structure shown.

Moreover, the projection or rise upon the floor adapted to cooperate with swinging member 5 may take any form that will produce the desired results. In the event the floor is carpeted, bolt 20 may be provided with a washer or flat plate 25 disposed below head 19 so that carpet 26 may be held firmly under head 19 and not be disturbed by the use of this bolt.

A variant embodiment of the invention is illustrated in Fig. 6. Member 5 is provided with a solid rubber tip 27 adapted to engage and ride upon a rise 28 secured to the floor. Rise 28 forces swinging member 5 to its vertical position, as shown, so that it will be latched in this position by being forced to the right beyond detents 17. The frictional engagement between rise 28 and tip 27 can be made sufficient to hold the door in open position, as well as arresting its open movement to act as a stop.

In this connection, it is pointed out that the invention does not limit the construction of tube 15 to a hollow structure, as illustrated in Figs. 2 and 3. Tube 15 may be solid with its lower end provided with a recess 29 of sufficient depth to permit bolt head 19 to be received therein.

From the foregoing description, it will be apparent that a novel type of door stopping and holding device is disclosed that is simple, sturdy and inexpensive to construct. The parts are small and compactly arranged. If desirable, a cover 30 may be provided to extend over and upon bracket 8, as illustrated in Figs. 1 and 2. Legs 12 are preferably slanted along their front edge so that this front edge may be approximately parallel to the position assumed by swinging member 5 when it is free from the floor projection 19. Cover 30 gives the device a somewhat streamline hooded appearance. It substantially encloses swinging member 5, which is the only movable part of my device. It will be understood that this floor projection 19 need not be so large as to interfere with the use of the floor. As a

matter of fact, the extent of the projection from the floor is so inconsequential that this area about the door may be used without danger of tripping.

Without further elaboration, the foregoing will so fully explain the gist of my invention that others may, by applying current knowledge, readily adapt the same for use under varying conditions of service, without eliminating certain features, which may properly be said to constitute the essential items of novelty involved, which items are intended to be defined and secured to me by the following claims.

I claim:

1. Means for stopping a door in its opening movement and for holding it open at the position it is stopped comprising a projection on the floor, a swinging member carried by the door near the lower part thereof adapted to engage said projection, and means for latching said swinging member upon engaging said projection in a door holding position.

2. Means for stopping a door in its opening movement and for holding it open at the position it is stopped comprising a projection on the floor, a swinging member carried by the door near the lower part thereof adapted to ride upon said projection in the opening movement of the door, there being means on said swinging member to receive said projection, and means for latching said swinging member in a door holding position after it has received said projection.

3. Means for stopping a door in its opening movement and for holding it open at the position it is stopped comprising a bracket adapted for attachment to the door near the lower part thereof, a locking member pivotally mounted on said bracket for swinging movement away from the door, the lower portion of said locking member being provided with means for engaging and riding upon a projection on the floor in the opening movement of the door, and means on said bracket for latching said locking member in a door holding position as said locking member rides upon said projection.

4. Means for stopping a door in its opening movement and for holding it open at the position it is stopped comprising a bracket adapted for attachment to the door near its lower part, a locking member pivotally mounted upon said bracket for swinging movement away from said door and having its lower end open, there being means limiting the swinging movement of said locking member away from the door, a projection on the floor adapted to be received in said open end of said locking member as the latter rides upon said projection in the opening movement of the door, and means for carrying said locking member in pivotally mounted relation upon said bracket, said means providing for relative adjustment of said locking member to locking hold its said lower end at a predetermined height from the floor with respect to said projection.

5. Means for stopping a door in its opening movement and for holding it open at the position it is stopped comprising a bracket adapted for attachment to the door near its lower part, a locking member pivotally mounted upon said bracket for swinging movement and having its lower end open, a projection on the floor adapted to be received in said open end of said locking member as the latter rides upon said projection in the opening movement of the door, and a pair of opposed detents on said bracket yieldably hold-

ing said locking member in a position over said projection to hold the door in open position.

6. Means for stopping a door in its opening movement and for holding it open at the position it is stopped comprising a substantially U-shaped bracket having its cross leg adapted for attachment to the door, a locking member pivotally supported by the opposed legs of said U-shaped bracket, said locking member being arranged to swing between said opposed legs and outwardly from said cross leg and to assume a vertical position parallel to said cross leg when in its locked position, said bracket being mounted upon said door to space the lower end of said locking member a predetermined distance above the floor when said locking member is in vertical position, a projection adapted to be mounted on the floor in the path of said locking member whereby said lower end thereof will engage and ride upon the same to move said locking member to a vertical position, and detents on said opposed legs past which said locking member is forced when moved to a vertical position by the engagement of its said lower end with said projection.

7. Means for stopping a door in its opening movement and for holding it open at the position it is stopped comprising a substantially U-shaped bracket having its cross leg adapted for attachment to the door, a locking member pivotally supported by the opposed legs of said U-shaped

- 5 bracket, said locking member being arranged to swing between said opposed legs and outwardly from said cross leg and to assume a vertical position when in its locked position, means for adjusting said locking member vertically with respect to its mounting whereby to predetermine the spacing of the lower end of said locking member from the floor when in its vertical position, and means for latching said locking member in 10 its vertical position to hold the door open.
8. Means for stopping a door in its opening movement and for holding it open at the position it is stopped comprising a substantially U-shaped bracket having its cross leg adapted for attachment to the door, a locking member pivotally supported by the opposed legs of said U-shaped bracket, said locking member being arranged to swing between said opposed legs and outwardly from said cross leg and to assume a vertical position 15 when in its locked position, means for adjusting said locking member vertically with respect to its mounting whereby to predetermine the spacing of the lower end of said locking member from the floor when in its vertical position, and means for latching said locking member in 20 its vertical position to hold the door open, said means yielding to a forcible movement of the door to closed position to release said locking member from vertical position.

GEORGE G. WYCKOFF.
